UNITED STATES PATENT OFFICE.

HERMENEGILDE CARRIER, OF AMESBURY, MASSACHUSETTS, ASSIGNOR TO G. W. J. MURPHY COMPANY, OF AMESBURY, MASSACHUSETTS, A CORPORATION OF MASSACHUSETTS.

CHECK FOR DOORS.

Application filed September 26, 1924. Serial No. 740,051.

This invention relates to door checks or stops and the object is to provide an efficient device of this character for application to doors, particularly to the doors of vehicles with closed bodies, to limit the opening movement thereof. The particular embodiment of my invention chosen for purposes of illustration herein by way of example might be considered an improvement on the device shown in my copending application, Serial No. 710,854, filed May 3, 1924.

My invention will best be understood by reference to the following description of one form thereof shown in the accompanying drawings, wherein:

Fig. 1 is a horizontal section through a portion of the hinge pillar of a vehicle body and the adjacent portion of the door, the door being in open position;

Fig. 2 is a similar view with the door closed;

Fig. 3 is a side elevation of the stop with the parts extended in alignment, the view being on a larger scale; and

Fig. 4 is a plan of the stop.

My invention relates to a device for limiting the opening movement of a door so that it will not swing open too far and is herein shown as applied to a stop of the type shown in my copending application above referred to and which takes the form of a series of hinge leaves 7, 9, 11 and 13, the leaves 9 and 11 being adapted to extend as shown in Fig. 1 between points of the hinge pillar 15 and hinge style 17 which separate from one another in the opening movement of the door, and to form a foldable connection adapted to lie between the pillar and style and be housed in suitable mortises therein when the door is shut, as shown in Fig. 2.

It will be obvious that as the leaves 9 and 11 come into alignment they serve as a connection across this angle between the door and the hinge pillar and prevent further swinging movement of the door about its hinges 19. The leaves 7 and 13 provide convenient means for securing the ends of the leaves 9 and 11 to the door and to the hinge pillar, they being preferably attached by screws to the inner faces of the same, as shown in Figs. 1 and 2 of the drawings.

To prevent the toggle formed by the leaves 9 and 11 (see Fig. 1) from throwing over past dead center and further to minimize the

effect of the shock which is thrown on the stop by its action in halting the swinging movement of the door a flat spring 19 may be riveted to leaf 11 in such a manner that its end extends past the hinge joint between the leaves 9 and 11 and is presented to the back of the leaf 9 so as to come in contact therewith and bear thereagainst when the leaves assume the position shown in Fig. 1 shortly before they come into alignment and to yield resiliently when the links are straightened out into alignment as shown in Fig. 3. This arrangement permits the door to open freely but as the leaves come to the position of Fig. 1, the movement is cushioned, a sharp shock is not thrown on the parts and the reaction of the spring tends to return the leaves to the position shown in Fig. 1 slightly off dead center so that in the closing movement of the door they collapse to the position shown in Fig. 2.

The present invention more particularly relates to means for preventing any noise or rattling of the parts. A stop of the present kind finds particular application to the doors of motor vehicles which are in continuous vibration and any looseness or play in any accessories of such a vehicle causes a disagreeable rattle. I therefore provide suitable means for cushioning the parts of the stop and this may conveniently be designed to exert a pressure upon the hinge leaves binding them on their pintles to prevent any rattling. Herein I have shown a flat bowed spring 21 secured at one end to the inner face of the leaf 11 and adapted to be presented to the opposed face of the link 9 when the parts are in the closed position shown in Fig. 2 so as to be compressed between the two leaves. By this arrangement the spring creates a pressure against the three pintle pins which prevents any of the parts from rattling.

I prefer to utilize a flat spring 21 interposed between the two leaves as herein shown as it may form a unit with the series of leaves, as shown in Fig. 3, and presents a smooth surface when the door is open, as shown in Fig. 1, without any projecting parts or corners which might catch in clothing. In the example shown the spring 21 is applied to the same leaf as the spring 19 and may be secured by the same rivets 23.

I have described in detail the particular

embodiment of my invention shown by way of example in the accompanying drawings. Obviously the details of mechanical construction may be considerably varied without departing from the spirit of the invention.

What I claim as new and desire to secure by Letters Patent I shall express in the following claims.

- 10 1. A door stop comprising a pair of hinged leaves provided with means for connecting them to the hinge pillar and hinge style, said leaves adapted to fold between pillar and style when the door is closed and extend substantially diagonally therebetween when open and resilient means interposed between the leaves and adapted to be compressed therebetween when the door is closed.
- 20 2. A door stop comprising a pair of hinged leaves provided with means for connecting them to the hinge pillar and hinge style, said leaves adapted to fold between pillar and style when the door is closed and extend substantially diagonally therebetween when open and cushioning means carried thereby and interposed between the adjacent

faces of the leaves when the door is closed.

3. A door stop comprising a pair of hinged leaves provided with means for connecting them to the hinge pillar and hinge style, said leaves adapted to fold between pillar and style when the door is closed and extend substantially diagonally therebetween when open, a spring secured to one leaf and having an end presented to engage the other as the leaves approach alignment, a spring secured to the opposite face of said one leaf and presented to the other as the leaves close and common means for securing the springs.

4. A door stop comprising a pair of hinged leaves provided with means for connecting them to the hinge pillar and hinge style, said leaves adapted to fold between pillar and style when the door is closed and extend substantially diagonally therebetween when open and spring means disposed when the door is in closed position to act on the leaves to cause a binding pressure of the same on their pivot but being relieved of pressure when the door is slightly open.

In testimony whereof, I have signed my name to this specification.

HERMENEGILDE CARRIER.
